VACUUM HOLDER FOR SHEETLIKE
MEMBERS

Stephen N. Wekeman, Saddle River Township,
Bergen County, N. J., assignor to General Print-
ing Ink Corporation, New York, N. Y., a corpo-
ration of Delaware

Application July 17, 1942, Serial No. 451,267

10 Claims. (Cl. 248—363)

My invention relates to a holder to which sheet-like members are held by action of suction.

My invention has particular reference to a vacuum holder so constructed and arranged that any one of a plurality of different sized sensitized films, or equivalent, may be held in engagement with the operative face thereof, the holding vacuum effect being applied to said films only in an area immediately adjacent the border or margin thereof.

Various other objects, advantages and characteristics of my invention will become apparent from the following detailed description.

My invention resides in the vacuum holder, features, combinations and arrangements of the character hereinafter described and claimed.

This application is a continuation in part of my prior application Serial No. 359,938, filed October 5, 1940.

For an understanding of my invention and for an illustration of some of the forms thereof, reference is to be had to the accompanying drawing, in which:

Figure 1 is a front elevational view showing a vacuum holder as constructed in accordance with one form of my invention;

Fig. 2 is an enlarged, vertical sectional view, partly in elevation, showing a part of the vacuum holder of Fig. 1;

Fig. 3 is a front elevational view showing a vacuum holder of another form; and

Fig. 4 is a vertical sectional view, partly in elevation, showing a part of the vacuum holder of Fig. 3.

Referring to Figs. 1 and 2, *b* represents a plate formed from aluminum or other equivalent material. The plate *b*, on one plane surface thereof, comprises a suitable number of endless grooves or channels *b1*.

In accordance with the invention, each groove *b1* is utilized for applying suction to a sensitized film, or equivalent, as hereinafter particularly described. As shown, each groove *b1* defines or borders an area on the outer surface of the plate *b* having generally oblong, rectangular configuration although it is to be understood that the invention is not to be limited in this respect. Further, as shown, the areas of said plane surface of the plate *b*, as defined by the respective grooves or channels *b1*, are of different sizes, respectively. Thus, the innermost groove or channel *b1* defines or borders the smallest area of the outer surface of the plate *b*. The next adjacent groove or channel *b1* defines or borders the next smallest area of said plate *b*, i. e.,

that area defined by the innermost groove or channel *b1* and also an area outwardly thereof. Similarly, the other grooves or channels *b1* define progressively increasing areas of the outer surface of the plate *b* and, as will be noted, these areas are symmetrically related to each other. However, the invention is not to be limited to this particular arrangement since, in a broader aspect, my invention contemplates the provision of grooves or channels *b1* which define areas of the plate *b* entirely separate from each other.

Viewed from a somewhat different aspect, my invention contemplates the provision, on the outer plane surface of the plate *b*, of sets of grooves, four grooves in each set, each set of grooves defining substantially a rectangular area on said plane surface. In the appended claims, the expression "rectangular area" shall be understood as generically descriptive of a square area wherein all sides are of equal length as well as an oblong, rectangular area.

As shown in Fig. 2, a block or member *t* is bolted or otherwise suitably secured to that surface of the plate *b* opposite the surface having the grooves *b1* formed therein. Each of the grooves *b1* communicates with a passage *b2* which extends transversely through the plate *b* and communicates, respectively, with the narrowed ends of threaded passages *t1* extending transversely through the block *t*. Each of the passages *t1* receives a threaded bolt *u* which coacts with a spherical member *v* adapted to seat upon the adjacent semi-spherical, passage surface *t2*. Extending longitudinally through the block *t* and communicating with all of the passages *t1* is a passage *t3* closed at one end, at its other end receiving a threaded nozzle *w* to which one end of a flexible pipe *x* may be secured.

An important preferred application of the present invention involves the use of the vacuum holder herein described for supporting a sensitized film operatively in the path of the projecting light beam passing through the objective lens of a camera. Suitably positioned handles, not shown, may be provided for elevating the vacuum holder to such position that the channeled surface of the plate *b* faces the camera objective lens.

In the example shown in Fig. 1, the film *F* which is to be associated with the holder is indicated as being of such size that it covers all of the grooves or channels *b1* except the outermost one, the border or margin of said film

F extending somewhat beyond the groove or channel b_1 which is most closely adjacent the film outer surface. With a film F of this size, the operator operates all of the screws u with the exception of that screw u associated with the groove or channel b_1 at the margin of the film F, to cause the respective spherical members v to be seated in closing relation as regards the respective associated passages b_2 . It will be observed that each of the screws u comprises a transverse passage u_1 , the arrangement being such that when any screw u is holding the associated spherical member v on its seat, the passage u_1 is alined, or substantially so, with the main passage t_3 . Accordingly, with the parts positioned as shown in Fig. 2, only that groove or channel b_1 with which the border of the film F is associated is in communication with the pipe x , this path of communication comprising the passages u_1 of the two outermost screws u .

With the arrangement described, a suitable vacuum pump, not shown, is connected to the flexible pipe x and operated to draw air toward the vacuum pump from said last named groove or channel b_1 through the passage t_3 , including the two outermost passages u_1 , and through the nozzle w . The border of the film F rests on the last named groove or channel b_1 and, as a result, by action of the vacuum pump on said last named groove or channel b_1 , a suction effect is applied thereto whereby said film F is held in operative position on the plate b.

With an arrangement of the character described above, the film F is held by action of suction only at the margin thereof. Accordingly, by my invention, there is an absence of embossing or indenting of the film throughout the operative surface thereof. This is a serious defect which usually occurs when the entire area of the film is subjected to a suction effect as in prior art practice.

As described above, the vacuum holder of my invention comprises a plurality of endless grooves or channels b_1 and, therefore, there is wide latitude as regards the sizes of the films F which may be associated with said vacuum holder while still holding the various films thereto by action of suction only at their respective margins or borders. Thus, the innermost groove or channel b_1 serves to hold the film F in operative position on the vacuum holder and, under such circumstances, all of the screws u_1 are disposed in seating relation on their respective associated spherical members v with the exception of the lowermost screw u , Fig. 2. The outermost groove or channel b_1 serves to hold a large film F on the vacuum holder and, at this time, all of the spherical members v are held in closing position by their respective screws u with the exception of the uppermost spherical member v , Fig. 2. Between the innermost and outermost grooves or channels b_1 , a number of different sized films may be accommodated as will be obvious.

Referring to the form of my invention illustrated in Figs. 3 and 4, the plate b hereinbefore described has a face plate f associated therewith. Adjacent plane surfaces of these plates are secured together in any suitable manner, as by the screws s_1 , or equivalent. Preferably, the plate f, the same as the plate b, is formed from aluminum or equivalent material and, in accordance with the invention, contacting surfaces of the respective plates, prior to assembly thereof, are coated with a suitable cement so as to insure a sealed joint between such contacting surfaces. The as-

sembly comprising the plates b and f constitutes a vacuum holder of an improved form for a sensitized film, or equivalent, as hereinafter particularly described.

As illustrated, the plate b, on the surface thereof facing the plate f, comprises a suitable number of endless grooves or channels b_1 corresponding with the grooves or channels b_1 hereinbefore described and sealed from each other by the otherwise contacting surfaces of the plates b and f. Extending through the plate f are a plurality of rows of passages f_1 which communicate, respectively, with the grooves or channels b_1 , each row of passages f_1 , corresponding in configuration with that groove or channel b_1 associated therewith.

In accordance with the invention, each groove or channel b_1 and the row of passages f_1 associated therewith forms an arrangement for applying suction to a sensitized film, or equivalent, in generally the same manner as hereinbefore described with respect to the form of the invention shown in Figs. 1 and 2.

As shown particularly in Fig. 4, a plurality of internally threaded passages p_1 , preferably vertically alined, extend through the plate b and these passages communicate, respectively, with the grooves or channels b_1 . Threaded into each of the passages p_1 is a nipple n_1 , the outer end of which is adapted to be sealed by a detachable cap c_1 formed from rubber, or equivalent.

The nipples n_1 , in any suitable manner, may be associated individually with any suitable vacuum pump or other source of suction, not shown. To this end, a flexible pipe a_1 leading to said vacuum pump may have one end of a nipple d_1 permanently connected to one end thereof by a clamping ring r_1 , the other end of said nipple d_1 carrying a tubular suction cap e_1 provided with a flared skirt section e_2 , Fig. 4.

The vacuum holder of Figs. 3 and 4 is utilizable in substantially the same manner as hereinbefore described with the vacuum holder of Figs. 1 and 2. Thus, as shown in Fig. 3, the particular film F, which is to be held on the holder after the latter has been properly positioned in a camera, or equivalent, is indicated as of such size that it covers all rows of the passages f_1 except the two outermost rows.

Accordingly, with the film F positioned as just described, the operator removes the cap c_1 from that nipple n_1 which is the third from the top as shown in Fig. 4, said last named nipple n_1 communicating with the row of passages f_1 covered by the film margin or border. Thereupon, the suction cap e_1 is associated with said last named nipple n_1 , the skirt section e_2 of said cap e_1 forming a seal on the rear surface of the plate b and, with the vacuum pump operating, air is drawn toward the vacuum pump through said last named nipple n_1 and from the groove b_1 together with the row of passages f_1 associated therewith. The film F, adjacent the border thereof, rests upon the last named passages f_1 and, as a result, by action of suction, said film F is held in operative position on the plate f.

The vacuum holder of Figs. 3 and 4 operates in generally the same manner as described above in connection with Figs. 1 and 2. Thus, with the holder of Figs. 3 and 4, the film F is held by action of suction only at the margin thereof, this being true by reason of the fact that the suction effect exists only in that nipple n_1 to which the vacuum pump is connected. Accordingly, with both forms of the invention, there is an absence of em-

bossing or indenting on the film throughout the operative surface thereof. Further, as will be obvious, the vacuum holder of Figs. 3 and 4 is susceptible of use for numerous sizes of the films F.

The provision of the caps c1 is important in connection with the invention. With the film F positioned as shown in Fig. 4, for example, the caps c1 should be associated with all of the respective nipples n1 below or inwardly of that nipple n1 with which the vacuum pump is associated. If this is not done, there may be, during operation of the vacuum pump, an undesired outward bulge of the film F along lines coinciding with the rows of passages f1 connected to the inner nipples n1. More particularly, when the vacuum pump is associated with that nipple n1 which is third from the top and with the film F positioned as shown in Fig. 4, operation of the vacuum pump causes air to be withdrawn from beneath said film whereby the latter closely hugs the adjacent plate surface. If the caps c1, or equivalent, were not utilized to seal the two lowermost nipples n1, atmospheric pressure applied therethrough would cause an outward spot or line bulge along lines coinciding with the two innermost rows of passages f1.

In view of the foregoing, it will be recognized by those skilled in the art that I provide vacuum holders of simple construction which are advantageously adapted to apply only a marginal holding effect to any one of a plurality of different sized films. The required operations are few in number and the number of parts requiring manipulation are small and capable of operation in a simple manner.

Better results are obtained with the vacuum holder of Figs. 1 and 2 in those cases where the requirements are such that films F differ only slightly in size. With such films, it is necessary for neighboring endless grooves or channels to be disposed rather closely together, for example, as shown with respect to the pair of grooves or channels b1 between the innermost and outermost ones, Figs. 1 and 2. Under these circumstances, it is desirable to use a holder such as illustrated in Figs. 1 and 2 rather than the one illustrated in Figs. 3 and 4.

Although the invention has been described in connection with the association of a sensitized film with a camera holder, it will be understood that the invention is not to be so limited. Thus, for example, the principles of my invention may be used for holding a copy sheet on the copy board of a camera, for holding a sensitized metal or other sheet-like member on the holder of a projector, for positioning a sensitized film in proper position in an enlarging box, etc.

In the appended claims, the references to "endless cavity means" shall be understood as generally describing the endless grooves or channels b1 and the endless rows of passages f1.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In a device of the character described, a plate structure having one plane surface thereof

shaped to form endless cavity means adapted to be covered by the marginal section of a sheet-like member, and means for applying a suction effect to said endless cavity means to thereby retain the sheet-like member in association with said plate structure, said sheet-like member, while thus associated with said plate structure, being retained in position only by the suction effect existing at said endless cavity means and said sheet-like member, in the area thereof within said endless cavity means, being free from any suction effect whereby such area is free from an embossing or indenting effect.

2. In a device of the character described, a plate structure having an endless groove extending therewith from one plane surface thereof, and means for applying a suction effect to said groove to thereby retain the margin of a sheet-like member in direct engagement with the edges of said groove to thereby seal the same, said sheet-like member, while thus associated with said plate structure, being retained in position only by the suction effect existing at said groove and said sheet-like member, in the area thereof within said groove, being free from any suction effect whereby such area is free from an embossing or indenting effect.

3. In a device of the character described, a plate structure having one plane surface thereof shaped to form a plurality of endless cavity means having progressively increasing size toward the border of said plate structure, said plate structure being adapted to have associated therewith individual sheet-like members of different sizes, one of said endless cavity means forming the border of an area of one size on said plane surface, another of said endless cavity means forming the border of an area of smaller size on said plane surface, said last named area being disposed within said first named area, and means for applying a suction effect to one of said endless cavity means to thereby retain the margin of a sheet-like member in direct engagement with said last named endless cavity means to thereby seal the same, said sheet-like member, while thus associated with said plate structure, being retained in position only by the suction effect existing at said last named endless cavity means and said sheet-like member, in the area thereof within said last named endless cavity means, being free from any suction effect whereby such area is free from an embossing or indenting effect.

4. In a device of the character described, a plate structure having one plane surface thereof shaped to form a plurality of endless cavity means having progressively increasing size toward the border of said plate structure, said plate structure being adapted to have associated therewith individual sheet-like members of different sizes, one of said endless cavity means forming the border of an area of one size on said plane surface, another of said endless cavity means forming the border of an area of smaller size on said plane surface, said last named area being disposed within said first named area, a plurality of separate means for separate communication with the respective endless cavity means, either of said communicating means being adapted to have a vacuum pump connected therewith to thereby retain the margin of a sheet-like member in sealing engagement with the endless cavity means to which the vacuum pump is connected, said sheet-like member, while thus associated with said plate structure, being retained in position only by the suction effect existing at said

last named endless cavity means and said sheet-like member, in the area thereof within said last named endless cavity means, being free from any suction effect whereby such area is free from an embossing or indenting effect.

5. In a device of the character described, a plate structure having extending thereinto from one plane surface thereof a plurality of endless grooves having progressively increasing size toward the border of said plate structure, said plate structure being adapted to have associated therewith individual sheet-like members of different sizes, one of said grooves forming the border of an area of one size on said plane surface, another of said grooves forming the border of an area of smaller size on said plane surface, said last named area being disposed within said first named area, and means for applying a suction effect to one of said grooves to thereby retain the margin of a sheet-like member in direct engagement with the edges of said last named groove to thereby seal the same, said sheet-like member, while thus associated with said plate structure, being retained in position only by the suction effect existing at said last named groove and said sheet-like member, in the area thereof within said last named groove, being free from any suction effect whereby such area is free from an embossing or indenting effect.

6. A vacuum holder for sheet-like members, said vacuum holder comprising a plate structure having one plane surface thereof shaped to form a plurality of endless cavity means having progressively increasing size toward the border of said plate structure, means for producing a vacuum effect in any one of said endless cavity means, and means for sealing each of the endless cavity means which is disposed within the endless cavity means subjected to the vacuum effect.

7. A vacuum holder for sheet-like members, said vacuum holder comprising a plate structure having one plane surface thereof shaped to form a plurality of endless cavity means having progressively increasing size toward the border of said plate structure, means for producing a vacuum effect in any one of said endless cavity means, and means for sealing each of the endless

cavity means which is disposed within the endless cavity means subjected to the vacuum effect, said last named means comprising a screw and a spherical passage-closing member associated with each endless cavity means.

5 8. A vacuum holder for sheet-like members, said vacuum holder comprising a plate structure having one plane surface thereof shaped to form a plurality of endless cavity means having progressively increasing size toward the border of said plate structure, a block on the opposite surface of said plate structure, said block comprising a passage extending longitudinally therethrough, a passage communicating with the block passage and with each endless cavity means, a spherical member for closing each communicating passage, and means for moving each spherical member to seating position.

20 9. In a device of the character described, a plate structure having a plane surface provided with a cavity means defining substantially a rectangular area on said plane surface, and means for applying a suction effect to said cavity means along all four sides thereof to thereby retain in association with said plate structure a sheet-like member having its marginal section covering all four sides of said cavity means, said sheet-like member, while thus associated with said plate structure, being retained in position only by the suction effect existing at said cavity means whereby said sheet-like member retains its plane configuration in the area thereof within said cavity means.

30 10. In a device of the character described, a plate structure having a plane surface provided with a set of grooves defining substantially a rectangular area on said plane surface, and means for applying a suction effect to said grooves to thereby retain in association with said plate structure a sheet-like member having its marginal section covering said grooves, said sheet-like member, while thus associated with said plate structure, being retained in position only by the suction effect existing at said grooves whereby said sheet-like member retains its plane configuration in the area thereof within said grooves.

STEPHEN N. WEKEMAN.
